UNITED STATES PATENT OFFICE

CHARLES W. POSPISIL, OF FULLERTON, CALIFORNIA

PORTABLE HAND SLICER AND CUTTER

Application filed July 22, 1926. Serial No. 124,238.

This invention relates to a slicing or cutting machine adapted for use in connection with materials and commodities generally and for instance meat and cheese.

- 5 It is aimed to provide a novel, efficient, durable, simple and comparatively inexpensive construction adapted to be guided and pushed by the hand and in which the blade is driven by an electric motor.
- 10 Another object is to provide a novel construction wherein the frame may be adapted to slide on a base or rest or travel on rollers, as selected.

With the foregoing and additional objects, 15 such as will become apparent as the description progresses, in view, the invention has been embodied in one operative form as illustrated in accompanying drawings.

- In said drawings:—
- 20 Figure 1 is a side elevation of the machine; Figure 2 is a side elevation reverse to Figure 1; Figure 3 is a plan view; Figure 4 is a sectional view taken on the 25 line 4—4 of Figure 1 showing the gear drive for the cutter blade disk; Figure 5 is a transverse sectional view taken on the line 5—5 of Figure 3 showing the thickness gage used in connection with 30 the cutting member; Figure 6 is an end elevation; Figure 7 is a front elevation; Figure 8 is a transverse sectional view 35 through the machine showing the same supported on the base or rest, and

- Figure 9 is a perspective view of said base or rest.
- Referring specifically to the drawings, a suitable form of supporting frame is provided as at 10 which may have a horizontal bed or plate 11 with a cutter-mounting wall 12 rising therefrom. Also, said frame has spaced parallel runners 13 depending therefrom. Axles 14, for instance in the form 40 of bolts, may be removably passed through the runners 13 and support wheels 15, adapted to rest on a bench, table or the like to reduce friction when the machine is operated.
- If preferred, the rollers 15 may be dispensed with by removing the axles or bolts

14, and the device slid along a base or rest 16, preferably stationarily fastened to a bench or table, and having grooves as at 17, slidably fitted by the runners 18.

The cutter or knife is shown in the form 55 of a disk or blade 18, preferably slightly dished as shown, and sharpened at its periphery. The disk or blade 18 extends below the surface of the bed or plate 11. Said disk is detachably carried on a short transverse 60 shaft 19. To this end, shaft 19 has a squared portion on which a collar 20 is detachably secured and which collar has a plurality of lugs or pins 21 extending therefrom and removably into openings 22 in the disk or blade 18. A nut or other fastening 23 prevents detachment of the plate or collar 20 from the shaft 19. Said shaft 19 in turn is journaled 65 and mounted against displacement in a sub-housing 24 carried by the wall 12 and extending from a housing 25 also carried by said wall 12. Disposed longitudinally of the housing 25 is a drive shaft 26 which carries a worm 27 within the housing and which meshes with a worm wheel 28 within housing 70 24 and keyed to the shaft 19. The shaft 19 is accurately fitted through the use of various thrust washers as at 29.

Said wall 12 has an offset portion as at 30, having a hole 31 therethrough whereby a 75 hand grip or handle is afforded. The wall 30 is extended and supports an electric motor 31' which drives the said shaft 26 and which receives its current from any suitable source.

A roller 33, is journaled on a suitable pin or shaft 34 carried by wall 12, and engages the cutter or disk 18 in such manner as holds the same from drawing in or becoming distorted. Such roller 33 is preferably made of 80 compressed or indurated fiber.

On the side of cutter or disk 18 opposite to the roller 33 is a slide adjuster in the form of a plate 35 having an elongated slot 36 laterally thereof and through which a bolt 37 passes and which is threaded to the plate 11. The advantage of the slide adjuster is to 85 make the slicing or cutting easier through close adjustment against the knife.

A slice adjuster plate is employed as at 90 40 and has a depending block 41 occupying a 100

slot 42, laterally enlarged with respect to the same, and formed in the plate 11. A bridge 43 extends across the slot and an adjusting screw rod 44 is journaled in said bridge and has threads at 45 engaging threads in the block or dependent 41. A hand wheel 46 is provided to facilitate manipulation. Thus through adjustment of the rod 44, the thickness adjuster or gage plate 40 may be moved closer to or farther away from the plane of the cutter 18, to thus regulate the thickness of the slice since the material is held against the plate 40 with the left hand while the operator slides the machine with the right hand, 15 engaging the same at the handle 30.

The machine is preferably cut away as at 45 on the discharge side thereof to facilitate the escape of cut material.

It is to be understood that the machine 20 may be made in various sizes and that no limitation is to be implied as to the material or materials which may be sliced or cut since such divergent materials have been cut as meat and cheese, and wall paper, the latter 25 being for the purpose of trimming.

Attention is called to the fact that the housings or boxings 24 and 25 are in separable sections suitably held together so that the various parts may be applied, inspected 30 or repaired.

Various changes may be resorted to provided they fall within the spirit and scope of the invention.

I claim as my invention:

35 A machine of the class described comprising a movable frame having a wall rising therefrom, a means extending from the frame and disposed laterally thereof engageable by the hand to facilitate reciprocation of the 40 frame, the latter means having an upward and forward extension, a motor fastened to said extension, casings secured to said wall, driving shafts and gearing in said casings, a cutter on one of said shafts, a slide adjuster 45 movable relatively to the cutter, a screw on said plate threaded to said slide adjuster and operable to vary the position thereof and runner members, said slide being adjustably supported on one of the runner members.

50 In testimony whereof I affix my signature.
CHARLES W. POSPISIL.
